JAW ASSEMBLY FOR VISES

Melmore Zugermayer, Southampton, Pa.

Application January 25, 1937, Serial No. 122,283

1 Claim. (Cl. 81—38)

The invention relates to a bench vise attachment and more especially to a jaw assembly for bench vises.

The primary object of the invention is the provision of an attachment of this character, wherein a four-jaw assembly can be used in connection with the bench vise so that work can be gripped or clamped at four points thereof to hold the work more firmly and securely and avoiding damage thereto resultant in the clamping of such work in the double jaw vise of the bench type.

Another object of the invention is the provision of an attachment of this character, wherein the same is susceptible of use in a horizontal plane or in a vertical position when associated with a bench vise so that work can be firmly and securely held without liability of the shifting or wobbling of such work when engaged in the attachment.

20 A further object of the invention is the provision of an attachment of this character, which in the assembly thereof is a unit in itself and is readily and easily applied to a bench vise for use therewith and in this manner converting the latter from a two-jaw to a four-jaw vise.

25 A further object of the invention is the provision of an attachment of this character, which is simple in its construction, thoroughly reliable and efficient in operation, strong, durable, and inexpensive to manufacture.

With these and other objects in view, the invention consists in the features of construction, combination and arrangement of parts as will be hereinafter more fully described, illustrated in 35 the accompanying drawing, which discloses the preferred embodiment of the invention and pointed out in the claims hereunto appended.

In the accompanying drawing:

Figure 1 is a plan view of the attachment constructed in accordance with the invention.

Figure 2 is a sectional view on the line 2—2 of Figure 1 looking in the direction of the arrows and showing the attachment in a vise.

Figure 3 is a sectional view on the line 3—3 of Figure 1 looking in the direction of the arrows.

Figure 4 is a fragmentary sectional view on the line 4—4 of Figure 1 looking in the direction of the arrows.

Similar reference characters indicate corresponding parts throughout the several views in the drawing.

Referring to the drawing in detail, A designates generally a conventional type of bench vise having the fixed and adjustable jaws 5 and 6, respectively, and operating opposite each other,

the adjustable jaw 6 being moved toward and away from the fixed jaw by a feed screw 7 as is usual.

The attachment comprises a bed plate 8 preferably of flat sided formation having the beveled corners 9 while centrally of this plate is a relatively large square shaped opening 10 while at one side edge of the said plate is an outwardly tapered centrally located extension 11.

Above the bed plate 8 are arranged the opposed equilateral triangular shaped jaw sections 12 and 13, respectively, these being in pairs and extended from the flat bottoms 14 of the sections 12 are downwardly extended abutment wings 15, these being bent at right angles from the inner edges of said sections 12 and are passed through the opening 10 in the bed plate 8. The wings 15 at opposite ends are carried beyond the opening 10 in the bed plate 8 while one of the sections 12 is riveted at 16 or otherwise made fast to the bed plate 8 while the other section is slidable upon said bed plate and to the slidable section 12 is connected at its longitudinal center a coiled retractile spring 17 which is also fixed at 18 close to the outer end of the extension 11, the spring 25 being designed to separate the sections 12 from each other to the extent of the opening 10.

The sections 12 and 13 at the diagonal edges thereof are formed with upturned flanges 19 and the said flanges on the sections 13 at their inner ends meet each other while the flanges 19 on the sections 12 at their inner ends are separated from each other.

The flanges 19 on the sections 12 are formed with guides 20 with which are interfitting the flanges 19 of the sections 13 and such flanges of both sections 12 and 13 constitute a four-jaw assembly for attachment to the vise A.

In the attachment of the four-jaw assembly, the wings 15 are inserted between the jaws 5 of said vise A with the wing on the fixed section 12 contacting with the fixed jaw 5 of said vise while the wing on the slidable section 12 contacts with the adjustable jaw 6 and thus on the turning of the screw 7 the slidable section 12 and the sections 13 will become adjusted relative to the fixed section 12 for increasing or decreasing the capacity of the four-jaw assembly for the firm securing of work within said assembly so that the work will be clamped at four points thereof or at four sides or faces of the same.

When the adjustable jaw 6 of the vise is moved away from the fixed jaw 5, the spring 17 by its tension becomes active to have the slidable sections 12 of the assembly separate and thus the 55

wings 15 of these sections 12 will be held in contact with the jaws of the vise A while the sections 13 slidably interfitted with the sections 12 will open correspondingly with the said sections 12.

5 12. What is claimed is:

A jaw assembly for a vise having a fixed jaw and a movable jaw, comprising opposed equilateral substantially triangular shaped sections, each 10 having an upturned outer edge flange, a flat sided bed plate having the said sections superimposed thereon and provided with beveled corners and a relatively large square shaped center opening, an outwardly tapered extension formed on said

bed plate, a coiled retractile spring having connection with said extension and one of the sections, guides formed on the outer edge flanges of a pair of the opposed sections and adjustably interfitting the flanges of the remaining opposed sections for effecting a four-jaw assembly, and 5 downwardly extending abutment wings engaged through the center opening of the bed and for contact with the jaws of the vise when interposed therebetween, one wing being carried by the section having the spring attached thereto and the other wing carried by the section opposed thereto. 10

MELMORE ZUGERMAYER.
